CLAIM

The ornamental design for a rack of a stabilizer, as shown and described.

DESCRIPTION

FIG. 1 is a front side perspective view of a rack of a stabilizer;

FIG. 2 is another side perspective view of the rack of the stabilizer;

FIG. 3 is a front side elevation view of the rack of the stabilizer;

FIG. 4 is a rear side elevation view of the rack of the stabilizer;

FIG. 5 is a left side elevation view of the rack of the stabilizer;

FIG. 6 is a right side elevation view of the rack of the stabilizer;

FIG. 7 is a top plan view of the rack of the stabilizer;

FIG. 8 is a bottom plan view of the rack of the stabilizer; and,

FIG. 9 is a usage state reference view when the rack of the stabilizer is used with a tripod.

The broken lines shown portions of a rack of a stabilizer that form no part of the claimed design. The broken lines seen in FIG. 9 are for the purpose of showing environmental structure, and form no part of the claimed design.

1 Claim, 9 Drawing Sheets
